UNITED STATES PATENT OFFICE.

LAMARTINE C. TRENT, OF SAN FRANCISCO, CALIFORNIA.

AIR-COMPRESSOR.

No. 878,579.

Specification of Letters Patent.

Patented Feb. 11, 1908.

Application filed March 31, 1906. Serial No. 309,051.

To all whom it may concern:

Be it known that I, LAMARTINE C. TRENT, a citizen of the United States, residing at the city and county of San Francisco, State of California, have invented certain new and useful Improvements in Air - Compressors; and I do hereby declare the following to be a full, clear, and exact description of the same.

The present invention relates to an improved apparatus for the compressing of air within a pressure cylinder through the medium of a centrifugally propelled body of liquid, which liquid acts as the medium for forcing or expelling air under pressure from within a rotating receiver into an air pressure cylinder, the rotating receiver being provided with a series of controlled outlets for the escape of the air and liquid from within the said receiver in the form of jet streams.

To comprehend the invention reference should be had to the accompanying sheet of drawings, wherein—

Figure 1 is a vertical sectional view of the pressure cylinder and of the air receiver rotatably mounted therein, the hollow shaft for imparting rotation to the receiver being partly broken away to disclose the valve seated therein for preventing the compressed air escaping from within the pressure cylinder into the hollow shaft; Fig. 2 is a cross sectional top plan view taken on line $x-x$ Fig. 1 of the drawings; and Fig. 3 is an enlarged detail sectional view of a portion of the receiver and one of its outlet nozzles.

In the drawings the numeral 1 designates the cylinder within which the air is compressed, which cylinder shall hereinafter be termed a pressure cylinder. The pressure cylinder is provided with a pressure gage 2, and a safety valve 3.

Through a stuffing gland 4 secured to the pressure cylinder 1, extends a hollow rotatable shaft 5, to which is secured the air receiver 6, into the interior of which receiver extends the open lower end of the shaft 5.

The receiver 6 in shape is substantially that of an inverted cone, which forms a gradually contracted upwardly extending annular passage 7 for flow of the air and water to be discharged therefrom.

In the upper edge of the receiver 6 is formed a series of outlets 9, within each of which is fitted an outlet nozzle 10, said nozzles being each provided with a controlling valve 11, for regulating the jet to be discharged therefrom.

Through the bottom of the receiver 6 extends a series of short curved supply pipes 12, which pipes discharge into the interior chamber of the said receiver.

From the bottom of the receiver extends a bearing stud 13, which rests and works within the step bearing 14.

Within the lower portion of the hollow shaft 5 is formed a valve chamber 15, the seat 15' of which is controlled by a vertically movable ball valve 16, which is loosely held within the valve chamber 15 by its stem 17.

Rotation is imparted to the hollow shaft 5 by any suitable means, preferably by a belt 17', working over a pulley 17'', secured to the upper projecting end portion of the said shaft.

Into the hollow shaft 5 extends an air supply pipe 18, the lower end of which pipe terminates immediately above the valve seat 15. With this pipe, outside of the hollow shaft 5, connects a water supply pipe 18', which supplies a small quantity of water to said pipe.

In order that the water entering the chamber 19 through the supply pipes 12, may be confined and directed toward the outer wall of the receiver 6, there is secured within the said chamber 19 a deflecting disk 20, which forms a contracted annular passage 20' for the inflowing water.

In operation, the pressure tank or cylinder 1 is supplied with water so as to partially cover the receiver 6. Power is then applied for rotating the shaft 5 at a high speed for rapidly revolving the receiver 6 within the pressure tank or cylinder 1. During the rotary movement of the receiver, water is forced therein through the short curved supply pipes 12, the water entering therein impinging against the under surface of the deflecting disk 20, and being deflected toward the side wall of the chamber 19. At the same time, the air and water entering through the hollow shaft 5, is discharged into the said chamber 19, which, with the water deflected toward the side wall of the chamber, is by centrifugal force, thrown upward toward the upper edge of the receiver. The air being lighter than the water will move in advance thereof, the water moving upward at a high and increasing velocity within the gradually contracting passage 7, will act as

the medium for forcing the air under pressure through the outlet nozzles 10, into the pressure tank or cylinder 1, within which the air

is gradually compressed by the jet streams issuing from the nozzles 10. The water contained within the discharged jets intermingles with the body of water therein, while 5 the liberated air is held above the body of said water. The air thus forcibly ejected into the pressure tank or cylinder 1, is compressed therein by the jets continually forced from within the rotating receiver 10 through the outlet nozzles. The vacuum created within the receiver 6 during the outflow of fluid therefrom, causes the air to be compressed to be drawn therein, while the high speed at which the receiver is rotated, 15 causes the air and water contained therein to be discharged by centrifugal force under high pressure and, as before stated, the outwardly moving body of water serving as the medium for discharging the air from within 20 the receiver under pressure.

The size or area of the outflowing jets is regulated by the controlling valve 11, of the nozzles 10.

When the apparatus is at rest, the compressed air is prevented from escaping back 25 through the pipe 5, by means of the vertically movable ball valve 16, which valve is raised by the pressure of the air thereagainst, and forced firmly against its seat 15', thus 30 closing the same against the escape of air.

When the air within the tank or cylinder 1 has reached a given pressure, as indicated by the gage 2, an excess of pressure is relieved by the safety valve 3.

35 Inasmuch as a small quantity of water is admitted into the receiver with the air, it is apparent that such supplied water will, in time, raise the water within the pressure tank or cylinder 1, above a given level. To 40 provide for this, a valve controlled outlet pipe 21 is provided. When the water is raised within the pressure tank or cylinder 1, above a given level, the valve 22 is opened and the water permitted to escape through 45 the pipe 21, until the proper amount of water has been withdrawn from within the pressure tank or cylinder.

50 The water as delivered through the hollow shaft is thrown outwardly by centrifugal force, the moment it enters the receiver. This body of water confines the air entering therewith towards the upper surface of the receiver, and forces the same to move upwardly beyond the periphery of the deflecting plate or disk 20, where it is met by the moving body of water discharged under pressure from within the annular passage 20', and by such moving body forced upwardly within the contracted passage-way

within said tank or cylinder and raises the pressure thereof in accordance with the gradually increased pressure of the air compressed within the said tank or cylinder. The result is that the water taken into the receiver during the rotary movement thereof through the supply pipes 12, enters under a pressure proportionate to the pressure of the air within the tank or cylinder. In order that this pressure of the inflowing water may be conserved, is the main reason for the introduction of the deflecting plate or disk 20, within the receiver 6, which deflecting plate or disk forms, as before stated, a contracted annular passage 20' within which the inflowing water 70 moves under pressure. If the inflowing water was admitted directly into the enlarged interior chamber of the receiver, at the center thereof, the result would be a loss of its pressure; hence the reason for confining the same within a contracted annular passage way, until its point of discharge has been reached.

75 The water admitted through the supply pipe 18' is mainly for the purpose of maintaining cool the body of water within the pressure tank or cylinder. If fresh water is not admitted into the apparatus, the initial body of water contained within the pressure chamber or cylinder would quickly become 80 heated, under compression, resulting in a loss of efficiency. To obviate this, cool water is admitted into the receiver and discharged therefrom into the pressure tank or cylinder, which maintains the body of water contained 85 within said tank or cylinder at an even temperature.

90 Having described the invention what is claimed as new and desired to be secured by Letters Patent is—

1. An apparatus for the described purpose, the same comprising a pressure tank or cylinder, a receiver rotatably mounted therein, an inlet in said receiver for the admission of water, an air supply for admitting air to the 95 interior of the receiver at the point of the admission of the water, outlets in the receiver for the escape of air under pressure, an auxiliary water inlet for said receiver connecting with the interior of said tank or cylinder and 100 means for imparting rotation to the said receiver for centrifugally forcing air and water therefrom under pressure into the pressure tank or cylinder.

105 2. An apparatus for the described purpose, the same comprising a pressure tank or cylinder, a receiver rotatably mounted therein, inlets for admitting air and water into the receiver, outlets for the escape of air and water

or cylinder, of a receiver rotatably mounted therein, into which receiver air and water are received and discharged directly therefrom under pressure into the pressure tank or cylinder, said receiver comprising oppositely disposed connected upwardly inclined annular walls, and an intermediate annular deflector disk constituting in connection with one of said walls a restricted passage and means for imparting rotation to the receiver for centrifugally expelling the air and water therefrom.

4. The combination with the pressure tank or cylinder, of a receiver rotatably mounted therein and comprising oppositely disposed connected annular walls, devices for supplying air and water to the interior of the receiver, a deflecting disk or plate within the receiver, inlets below said disk or plate for admitting a compressing body of liquid into the receiver, outlets in the receiver for the escape of air and water from within the receiver under pressure, and means for imparting rotation to the receiver for centrifugally expelling air and water therefrom under pressure.

5. In an air compressor, the combination with a pressure tank or cylinder, of an annular cup shaped receiver rotatably mounted therein for receiving air and water and ex-

pecting the same therefrom under pressure into the said pressure tank or cylinder.

6. The means for compressing air within a pressure tank or cylinder, the same consisting of a receiver which receives air and liquid and expels the same therefrom under pressure into the pressure tank or cylinder, a horizontal deflector in said receiver for the water, and devices for rotating the receiver at a high speed to expel the air and water therefrom centrifugally.

7. An air compressor comprising a pressure tank or cylinder, a rotatable receiver for discharging air and water into the said tank or cylinder under pressure, said receiver comprising oppositely disposed connected walls, and a diaphragm therebetween, inlets in said receiver for the admission of air and water to the interior thereof, outlets for the escape of air and water therefrom under pressure, and means for rotating the receiver at a high speed for expelling the air and water therefrom centrifugally.

In testimony whereof I have hereunto affixed my signature in the presence of witnesses.
